LOUIS J. CHARLAND, OF RICHMOND, VERMONT, ASSIGNOR TO THE BORDEN COMPANY, OF NEW YORK, N. Y., A CORPORATION OF NEW JERSEY.

CAN-SOLDERING MACHINE.

Application filed June 21, 1920. Serial No. 390,486.

To all whom it may concern:

Be it known that I, LOUIS J. CHARLAND, a citizen of the United States, and a resident of Richmond, in the county of Chittenden and State of Vermont, have invented a new and useful Can-Soldering Machine, of which the following is a specification.

My invention relates to those machines by aid of which are soldered together the sides and the flanges of the ends of cylindrical metallic cans, and the objects of my invention comprise provision of means whereby such soldering can be accomplished more rapidly and perfectly, and with greater economy of labor, power and solder than heretofore.

I attain my objects by aid of the mechanism illustrated in the accompanying drawings, in which—

20 Figure 1 is a side elevation of the machine;

Figure 2 illustrates a cross-sectional view at the line 2—2 of Figure 1, viewed in the direction of the arrow, and the parts shown 25 being on enlarged scale;

Figure 3 illustrates a cross-section taken on the line 3—3 of Figure 1, viewed in the direction of the arrow;

Figure 4 is, on enlarged scale, a plan, or 30 top, view, of the solder trough and adjacent parts;

Figure 5 is a cross-sectional view illustrating diagrammatically a modified form of parts of the apparatus;

35 Figure 6 is, on enlarged scale, a central longitudinal sectional view illustrative of the cans referred to; and

Figure 7 is, on still more enlarged scale, a detail fragmentary, cross-sectional view 40 illustrative of the projection of the solder above the guide tracks.

The cans, C, C, to which my invention relates are of the well known type illustrated in Figure 6 of the drawings, and consist usually of a cylindrical member known as the "body", b, (constituting the "sides", b', of the can), the two otherwise open opposite apertures of the body being each respectively enclosed by one of the two members known as the "heads" or "ends", e, e, which latter are discs each provided with a therefrom angularly-projecting circumferential "flange", f, within which the body is, in assembling, telescoped; the parts being per-

manently secured together, or sealed, preferably hermetically, by means of molten solder, s, inserted to plug the interspace, or joint, between the interior of the flanges and the outsides of the body.

The types of metallic cans to which my invention especially relates comprise particularly those at present usually employed as containers of condensed, or evaporated, milk, the constituent sheet metal of which is of very thin gauge, say from .0091" to .0114" and from which it follows that the increment of diameter locally imparted to the cans by their flanges is practically negligible in the operation of my apparatus as hereinafter described.

Numerous apparatuses usually comprehensively designated as "floaters" have, with more or less efficiency and economy, been hitherto employed to effect application of the molten solder to the joints. All of these have, of course, comprised, for the solder, an elongated container variously referred to as the "trough", the "tank", or the "bowl", etc. These troughs have, in industrial practice, been hitherto substantially uncovered, i. e., widely enough open to admit of more or less actual immersion of substantial portions of the cans into the solder, as, for example, a considerable corner of the can thus including not only its joint but also parts of its sides, of both of its flanges, and of its head, or ends, the cans being, by aid of suitably disposed guide rails and conveyors, chains or belts, rolled forward through the solder in the trough while their axes of rotation are inclined to the horizontal. This has necessitated, in all cases, two similar operations or treatments, one for each of the two opposite joints of the can. These previous floaters are of the type shown, for example, in U. S. Letters Patent No. 1,022,770. By these former procedures much solder, in excess of what required to seal the joints, has been, in the trough, deposited and undesirably retained upon the flanges and ends of the cans, thereby necessitating several additional operations to remove it whether for appearance or economy or both; these operations including the now well known subjecting of the undesirably solder-smearred surfaces of the cans to the cleansing action of rotating brushes and involving a separate brush-

ing of not only each of their opposite sides and flanges, but also of each end.

It has also been attempted to reduce the amount of solder applied to the can by forcing a portion of the solder into a comparatively narrow channel venting above the level of the remainder of the mass within the trough, and by rolling the cans in such relation to the solder accumulated in such channel that the ends are not immersed; but in all the apparatus designed for this purpose, so far as known to me, there has been an intentionally greater, or less, accumulation at all times of solder within the channel, and a wasteful overflow of solder therefrom, the solder thus unapplied to the cans being undesirably cooled and particularly exposed to detrimental atmospheric influence.

My invention is based not only on my discovery that the joints can be more tightly, better, and more economically, sealed, without immersing any part of the can in the solder of the trough or contacting with solder unduly accumulated or retained in the channels referred to, provided my novel hereinafter described means are employed; but, also, upon my further discovery that when these means are employed, the solder can be successfully applied while the cans are being rolled forward with their axes horizontal, and thus simultaneously to both joints, thereby avoiding the above referred to duplications of the operation. Moreover, my procedure and means are such that normally no solder is contacted with the ends of the cans, nor with their flanges, except only momentarily during the brushing off of the inconsiderable, if any, surplus, the advantages of which will, I believe, be obvious without further amplification.

Basically considered my invention comprises the addition to the solder-container, or trough, 7, of an extendedly covering member, 7', hereinafter referred to as the cover, and against the under surface of which bears much of the mass, or bath, of molten solder. This cover may contain an opening, or inlet, 8, for therethrough supplying solder as required to the bath, or such inlet may be elsewhere located.

The cover may be connected with the trough in any convenient manner, but is, preferably, unitary therewith, being, as indicated in the drawings, a part of the same casting.

I provide the cover with an outlet 10, and, in extension thereof and, preferably, as a part of the cover, with a horizontally-longitudinally extending, therefrom upwardly projecting, spout, the, in this instance, upwardly projected longitudinal sides, or walls, of which are respectively indicated by 9, 9' in the drawings, and the longitudinal 65 top of which, embracing its free edges, 9'',

9'''', I use, in whole or in part, as a track, or guide, for the cans, having a tread well elevated above and free and clear of the top surface of the cover. I perforate said top by a longitudinally extended, but relatively constricted, (i. e., preferably not to exceed one-eighth of an inch wide) discharge opening, vent, or slot, 11 for delivery therethrough, and through the spout, of units of the solder from the molten mass thereof in 75 the trough, and their projection to contact with the cans.

It will be noted that the said vent 11 contacts with the tread of the track referred to as shown for example in Figure 7.

It may also be noted that by means of this construction the solder from the tank, at the moment of its delivery to the can, is raised not only above the main portion of the mass of molten solder below it, but is also elevated well above the top of the cover and to such an extent and in such a manner that accidental overflowings from the orifice if any, are by gravity promptly led away therefrom and to locations upon the top of 90 the cover undetimental to continuous, unclogged operation with thus unexposed solder, and whence readily recovered for future purification and use.

The tank and its contents are raised to, and maintained at, the usual temperatures for ensuring required liquescence of the solder by aid of any usual means, as for instance burners, 12, (Figs. 1 and 2), and the solder is, in any convenient manner, supplied to the tank through the inlet, 8, as by immersion therein of the end of a bar, 13, thereof, and automatically graduatedly, or otherwise, in any usual, well known, way, the level of the molten solder is constantly 105 maintained slightly above that of the discharge orifice, 11 and thus to ensure a continuous outflow of solder through said orifice in quantity as nearly as possible proportioned to what therefrom carried off by 110 the cans as hereinafter described. The operation is such that, under the conditions mentioned, the solder is, by gravity, abetted by the construction, forced up through the orifice, 11, and by reason of the relative 115 constriction of the passage, 10, and of the orifice, 11, and the cohesion of its molecules, caused to rise appreciably and, where and while uncontacted by a can, remain momentarily, above the orifice in the form of a correspondingly longitudinally extended laterally unsupported projection, or bulge, 8', (Fig. 7), of hemispherical cross-section, until the cohesion is, if ever, overcome by gravity sufficiently to cause overflow. This 125 constantly renewed projection of the solder importantly contributes to its proper application to the side of the can under the conditions specified, as, for example, in the respect, among others, that the said projection 130

of the solder is not allowed to otherwise accumulate, nor to stand, nor to overflow, exposed to oxidation or cooling, after its emergence from the orifice, or slot, of the spout; but, on the contrary, is normally, in its therefrom natant state, brought into essentially immediate contact with, and progressively carried off by, the cans.

It will be noted that the interior surfaces of the sides, 9, 9', of the spout incline toward each other, the passage, 10, being thus progressively upwardly constricted, which, I believe, also contributes to the projection of the solder and its remaining temporarily bulged above the orifice, as above described.

I have, in the foregoing, described the cover as being provided with only one of my above described combinations of spout and track, but it will be understood that, as shown in Figure 2, which illustrates my duplex and, for certain purposes, preferred form of the apparatus, a pair of these identical spouts disposed in mutual parallelism, are employed, this being the case when the solder is to be applied to both joints simultaneously of the cans, as above referred to.

It is of importance that, during the operation, the discharge orifices, 11, should be as nearly level as possible in the constructions shown in Figures 2 and 7, or, and also, at an indicated transverse inclination as shown in

Figure 5. In order to more certainly and readily attain and maintain such level, or also inclination, I construct the trough detached from, or movable relatively to the remainder of the apparatus, and provide means for readily imparting thereto, and thus to said orifices, their required horizontality, or also inclination. To this end, I provide means, each operated independently of the others, to respectively differentially raise or lower a different one of the four corner, or most corner-wisely projecting, portions of the trough, or solder container, relatively to the stationary frame, or base, of the apparatus. These means, in the present instance, comprise providing the trough with therewith connecting extensions, or arms, 14, projecting from adjacent the corners thereof over the top 15' or other stationary portion, or base, of the frame 15, the said frame being of any preferred construction suitable for the purpose. Through each arm 14 is threaded an adjusting leveling screw 16, carrying a usual lock-nut 16'. The lower, or free, ends of these screws bear upon the top of this relatively stationary supporting part, or base, and by turning them respectively as may be indicated not only is the required level, but also inclination, impartable to the orifices and to the therefrom projected bulge of the solder.

The cans are, as shown, rolled forward upon one, or both, of the treads 9", 9'", by aid of a usual suitable belt, or chain, 17,

bearing downwardly upon their sides and propelled from any convenient source of power, not shown.

I provide means, as is most important, to contribute to the support and guidance of the cans over my said spout-tracks, and therefrom projecting solder, in such positions as to ensure that their sides, as distinguished from their ends, or flanges, shall be presented to the delivery orifices and the therefrom issuing solder, and in such relation thereto that the bands of solder thereby applied shall be upon the sides only of the cans, but as nearly as possible to the joint without extending therefrom onto the flanges. To this end, I employ, in proper relation and position, any convenient, or usual, guide rails, 18, as, for example, as shown in Figures 1 and 2, a pair of oppositely disposed usual end-guide rails, or, in cases in which only one of my spouts is employed, and it is desired to treat the can in an inclined position, as shown in Figure 5, an additional rail, 18', may be employed as indicated in the drawing.

It will also be noted that in the construction illustrated in Figure 5, the mutually parallel edges of the apex of the spout constituting the track have been trimmed to a transverse inclination corresponding with that of the can.

The construction is such that the cans must be rolled forward over the solder vent while bearing and downwardly pressed upon at least one of the two threads of a track with which the edge of the vent contacts, and it is preferable to, in all cases, trim the treads relatively to each other so as to ensure as far as practicable under normal industrial conditions such bearing of the can throughout its run upon simultaneously both treads, and thus on each side of the vent, this obviously involving the making of more or less allowance to accommodate projection of the slight thickness of the flange beyond the surface of the sides. In Figures 2 and 5, the treads are intended to be shown as thus accommodated to the difference in diameter of the can at flange and side, and the treads of Figure 7 are to be understood subject to making such allowance, it being impossible to indicate the same accurately on a drawing of the scale and character of the drawing owing to the very great relative thinness of the metal, i. e., from .0091" to .0114" as above stated. But it will be understood that absolute exactness in difference of grade of the treads relatively to each other is negligible unless cans of unusually thick metal are involved, since the usual very small differences in diameter are insufficient to prevent the can from practically bridging the vent progressively and momentarily during the run.

It will be understood that an appropriate

flux has been, in any of the usual ways, suitably applied to the joints of the cans prior to their being rolled over my solder-supplying combination of spout and track, as above described. The cans are, as aforesaid, guided at this stage so as to ensure their taking up of the solder from the spouts in the form of a circumferential band located upon the sides of the can exclusively of any other parts thereof and in as close proximity as possible to the joints without substantially intruding upon the flanges. The usual co-action of the solder with the flux then occurs and is, to an extent, if not universally, sufficient to ensure the proper plugging of the joint by the solder; but I find it preferable, if not essential, in cases in which absolutely hermetic sealing is required, to combine with my said floater a therewith cooperating rotary brush, 19, or, in cases in which the cans have been treated horizontally and simultaneously at both joints, a pair, 19, 19', of such brushes, as indicated in Figures 1 and 3, these being mutually oppositely disposed behind, and having their axes of rotation parallel with, the slots of the tracks or guides, and their operative edges respectively disposed to sweep in opposite directions against the sides and the flanges in the direction of as distinguished from against, the respective ends of the cans. The brush, or brushes, are, as shown in the drawings, of the usual longitudinally extended form, respectively carried by shafts, 20, rotatorily mounted in a suitable stationary part of the apparatus, for example, in the instance shown in Figures 1 and 3, in the vertical sides, or walls, of a usual casing, 21, by which the cans, the brushes and the therefrom-flying solder are confined. Usual means for imparting rotation in opposite directions to the said shafts and their brushes are provided, as for example, the pulleys, 22, 22', carried by the shafts and usual belts, 22a, 22b, cooperating with said pulleys, and propelled by aid of a pulley, 22c, and therewith cooperating belt, 22d, from a source of power not shown. Usual means, for example, a belt, 23, are also provided to, in the usual manner, roll the cans forwardly between the brushes, such belt being actuated by usual means (not shown) and the cans being meanwhile supported on a usual track, 24, and guided by lateral end guide rails, 25, as shown. It follows from the construction described that a single treatment, by one brush only, of each end, or joint, of the can suffices to not only ensure the driving of the solder into any as yet insufficiently filled parts of the joint, but also to remove for future use all superfluous solder from that end of the can. It further follows that when the solder is applied simultaneously to both joints of the cans, as per my pre-

ferred construction shown in Figures 1 and 2, a single brushing operation during which the two brushes are acting simultaneously each respectively at an opposite end of the can, as shown in Figures 1 and 3, is sufficient, thus dispensing with the sequential and more numerous former brushings above referred to. 70

An incidental, but important, advantage of my above described construction is that the cans are not, as heretofore too often, unduly locally heated by the former actual, and relatively prolonged, immersion of parts thereof into the bath maintained at the melting point of the solder. To ensure, however, proper and more uniformly distributed temperatures throughout the cans during the operation, I employ, as may be indicated, pluralities, or groups, of usual gas burners, 26, disposed appropriately along the pathway of the cans so as to apply and maintain required heat. 80

Having now described my invention, what I claim as new and desire to secure by Letters Patent is the following, viz: 90

1. An apparatus for soldering cylindrical cans comprising a solder-container, or trough, having a cover provided with a horizontally-longitudinally extended, upwardly projecting, spout, the top of which is in part divided by a therethrough medial perforation; or slot, for the solder, into a bifurcated track for the cans having mutually parallel treads respectively bounding opposite sides of the slot; means to downpress the cans against simultaneously both of said treads and meanwhile roll them forward, and means to meanwhile feed solder upwardly through the slot continuously. 95

2. An apparatus for soldering cylindrical cans comprising a solder-container, or trough, having a cover provided with a horizontally-longitudinally extended, upwardly projecting, spout, the top of which is in part divided by a therethrough medial perforation, or slot, for the solder, into a bifurcated can-supporting track having mutually parallel treads respectively bounding opposite sides of the slot; means to downpress the cans against simultaneously both of said treads and meanwhile roll them forward; rails disposed to meanwhile guide the cans so that portions of their sides, as distinguished from their ends or flanges, shall pass over the slot, and means to meanwhile feed solder upwardly through the slot continuously. 110

3. In an apparatus for soldering cylindrical cans a solder-container, or trough, having a cover provided with a horizontally-longitudinally extended, therefrom upwardly projecting, spout, the top of which constitutes a can-supporting track medially divided into two mutually parallel, flat-surfaced, treads by a longitudinally extended, 125

relatively constricted, discharge opening, or slot, for delivery therethrough of solder from the trough; in combination with a rotatory brush disposed behind, and having its axis of rotation parallel with, said slot and its operative edge disposed to sweep the sides and flanges, as distinguished from the ends, of the cans; means bearing downwardly upon the cans to roll them forward bearing upon both of said treads simultaneously; means to ensure presentation to the slot of the sides of the cans, as distinguished from the ends, or flanges; and means to meanwhile feed solder upwardly through the slot continuously.

4. In an apparatus for soldering cylindrical cans, a solder-container, or trough, having an inlet for solder, and a cover provided with two horizontally-longitudinally extending, therefrom upwardly projecting spouts, the longitudinally extended tops of which constitute tracks, for the cans, and the operative surfaces of which are elevated above the upper surface of the cover and are each perforated by a relatively constricted discharge opening, or slot, for delivery therethrough of solder from the trough; in combination with a pair of mutually oppositely disposed, rotatory, spaced-apart brushes disposed behind, and having their axes of rotation parallel with said slots and their operative edges respectively disposed to sweep in opposite directions against the sides and flanges as distinguished from the ends of the cans; means contributing to movably support the cans over said slots with portions of their sides as distinguished from their ends or flanges presented thereto; means for forwardly rolling a plurality of cans simultaneously upon said tracks while so guided, and thence between said brushes; and means for meanwhile rotating said brushes.

5. An apparatus for soldering cylindrical cans comprising a relatively stationary frame, or base; a thereby movably supported solder container provided with a therefrom upwardly projecting spout having an elongated opening for solder bounded on each side thereof by portions of the topmost surfaces of the spout to constitute treads of a bifurcated track for the cans; means to roll the cans forward upon said treads while bearing upon both of them simultaneously; means to guide the cans while so rolling; means to meanwhile continuously feed solder upwardly through the slot to above the level of said treads; and respective means each independently operative to respectively raise or lower differentially from each other the four corners of the solder container relatively to said base, whereby the inclination of the plane of said opening and treads is indefinitely variable and adjustable.

6. An apparatus for soldering cylindrical cans comprising a relatively stationary frame, or base; a thereby movably supported solder container provided with a therefrom upwardly projecting spout having an elongated opening for solder bounded on each side thereof by portions of the topmost surfaces of the spout to constitute treads of a bifurcated track for the cans; means to roll the cans forward upon said treads while bearing upon both of them simultaneously; means to guide the cans while so rolling; means to meanwhile continuously feed solder upwardly through the slot to above the level of said treads; and respective means, comprising screws having their free ends bearing upon said base, each independently operative to respectively raise or lower differentially from each other the four corners of the solder container relatively to said base, whereby the inclination of the plane of said opening and treads is indefinitely variable and adjustable.

7. An apparatus for soldering cylindrical cans comprising a relatively stationary frame, or base; a thereby movably supported solder container provided with two mutually parallel therefrom upwardly projecting elongated spouts, each having an elongated opening for solder bounded on each side thereof by portions of the topmost surfaces of the spout to constitute the treads of a bifurcated track for the cans; means to roll the cans forward upon all of said treads simultaneously; means to guide the cans while so rolling; means to meanwhile continuously feed solder upwardly through the slots to above the levels of said treads; and respective means each independently operative to respectively raise or lower differentially from each other the four corners of the solder container relatively to said base, whereby the inclination of the plane of said openings and treads is indefinitely variable and adjustable.

8. In an apparatus for soldering cylindrical cans, a solder-container, or trough, having an inlet for solder, and a cover provided with a horizontally-longitudinally extending therefrom upwardly projecting spout, the longitudinally extended top of which constitutes a track for the cans having mutually parallel treads bounding laterally a relatively constricted discharge opening, or slot, for delivery therethrough of solder from the trough; in combination with means to continuously upwardly feed solder through the slot to above the level of said treads; means for forwardly rolling a plurality of cans simultaneously upon said treads while bearing upon both of said treads simultaneously; means to, while so rolling, guide the cans over said slot with portions of their sides as distinguished from their ends or flanges presented thereto;

a rotary brush disposed behind, and having its axis of rotation parallel with, said slot and its operative edge disposed to sweep against the sides and flanges, as distinguished from the ends, of the cans; means for forwardly rolling the cans while their sides are contacting with the brush; and means for meanwhile rotating the brush.

9. Apparatus for soldering cylindrical cans comprising a solder-container, or trough, having a cover provided with two mutually parallel, longitudinally-extended, upwardly projecting spouts, the top of each of which is divided by a therethrough medial perforation, or slot, for the solder into a bifurcated can-supporting track having two mutually parallel treads, the operative surfaces of all four of said treads being in substantially the same plane; and means to roll the cans forward while bearing on said treads.

10. Apparatus for soldering cylindrical cans comprising a solder container, or trough, having a cover provided with a therethrough upwardly projecting longitudinally extended spout having part of its top in the form of a track and containing a progressively upwardly constricted interior passage for solder venting where most constricted into contact with said track; means to continuously force solder from the trough to slightly above the level of said vent and of a tread of said track; and means to meanwhile downpress the cans upon said

tread and roll them forward, whereby solder is applied to the cans at the moment of its emergence from said passage.

11. Apparatus for soldering cylindrical cans comprising a solder container, or trough, having a cover provided with a therethrough upwardly projecting longitudinally extended spout having part of its top in the form of a track and containing an interior passage for solder having its vent in contact with a tread of said track; means to continuously force solder from the trough through said vent to above the level of said tread; and means to meanwhile downpress the cans upon said tread and roll them forward, whereby solder is applied to the cans at the moment of its emergence from said passage.

12. Apparatus for soldering cylindrical cans comprising a solder container, or trough, having a cover provided with a therethrough upwardly projecting longitudinally extended spout having a therethrough upwardly delivering longitudinally extended narrow slot, or vent, for the solder; means to roll the cans along said slot their sides in contact with the edge of the most constricted part thereof; and means to meanwhile force solder from the trough through said vent to above the level of its said edge whereby the solder is applied to the cans at the moment of its emergence from said most constricted part of said vent.

LOUIS J. CHARLAND.
